UNITED STATES PATENT OFFICE.

NATHAN KASDAN, OF NEW YORK, AND DANIEL POLLACK, OF BROOKLYN, NEW YORK,
ASSIGNORS TO MAJESTIC MACHINE & TOOL CO., INC., OF NEW YORK, N. Y., A COR-
PORATION OF NEW YORK.

Application filed January 18, 1923. (Serial No. 613,362.)

To all whom it may concern:

Be it known that we, NATHAN KASDAN, a citizen of Russia, and a resident of Bronx, in the county of Bronx, city and State of New York, and DANIEL POLLACK, a citizen of the United States, and a resident of Brooklyn, New York, have invented certain new and useful Improvements in Combination Vanity Articles, of which the following is a specification.

The object of the invention is to provide a novel combination vanity structure possessing a number of utilities and which may be conveniently carried and used as occasion may require.

The article of our invention comprises a box having a hinged lid and includes in its structure a housing for a lip-stick holder, a mirror and a compartment for a compact and a pad or a powder puff or similar articles, the housing for the lip-stick holder being extended crosswise of the box and receiving the body of said holder, while the slide within the holder has its button or head exposed for use in withdrawing the lip-stick holder from the housing and thereafter exposing the end of the stick for use, said exposed button or head also serving as an aid in preventing accidental displacement of the holder from said housing.

The box or case is preferably circular in outline and shallow and of a size to be conveniently carried in the hand or within the usual hand-bag carried by ladies.

The invention will be fully understood from the detailed description hereinafter presented, reference being had to the accompanying drawings, in which:

Fig. 1 is a plan view of a vanity case or box embodying my invention;

Fig. 2 is a vertical section through the same taken on the dotted line 2—2 of Fig. 1;

Fig. 3 is a vertical transverse section through the same taken on the dotted line 3—3 of Fig. 1; and

Fig. 4 is a similar section through the same taken on the dotted line 4—4 of Fig. 1.

In the drawings, 15 designates the body portion of a cylindrical case or box, and 16 the lid or cover portion thereof connected with said body portion by a suitable hinge 17 so that said lid or cover may be opened and closed at will. The body portion 15 may be utilized to receive one or more com-

pacts, a powder puff and the like. Within 55 the lid 16 is secured a mirror 18 by means of a tight fitting metal ring or band 19, said mirror being available for use when the lid 16 is opened from the body portion 15.

The lid 16 is of special construction in 60 that it has a central longitudinal portion thereof pressed upwardly to form an elongated housing 20 for a lip-stick holder 21, said housing being closed at its rear end by

the metal of the lid (Fig. 2) and open at 65 its front end (Figs. 1 and 2) to admit the lip-stick holder to the housing and permit the same, with the use of the usual knob or button 23, to be withdrawn from said hous- 70

ing whenever it may be desired to use the 75 lip-stick 22. The holder 21, stick 22 and button 23 are of commercial type and hence require no special description, but in the present instance the button 23 is utilized for the additional purposes of engaging 80 the front edge of the housing 20 to secure the holder within the housing and of facilitating the withdrawal of the holder from the housing. The housing 20 at its trans- 85

verse middle portions does not close under the sides of the holder 21, as shown in Fig. 3, but at its front and rear portions the metal of the housing is closed inwardly from opposite sides of the housing, as at 24, to pass below the outer side portions of the 90 holder 21 and afford close-fitting guides and supports for said holder, as well as means for maintaining the holder clear of the back 95 of the mirror 18. The lid 16 at the front of the housing 20 is concaved, as at 25, and inclined slightly downwardly toward the entrance to the housing, and this formation results in there being a retarding action between the surface 25 and the exposed end 100 of the holder 21 sufficient to yieldingly aid in securing the holder within the housing 20. The button 23 of the holder 21 is on positioning the holder within the housing 20 forced over the upper outer edge of the housing, pinching said edge and in that way 105 aiding to prevent accidental displacement of the holder from the housing.

We have indicated the holder 21 as a lip-stick holder, but we do not limit the invention to any particular cosmetic that may be held within the holder 21. While the holder 21 is a lip-stick holder, it may be employed for a cosmetic other than rouge, as, for in-

stance, a stick of black material for the eyebrows.

What we claim as our invention and desire to secure by Letters Patent, is:

- 5 1. A combination vanity structure of the character described comprising a shallow box having a displaceable cover and affording a container for toilet articles, said cover having as a part thereof a housing extending transversely of the box adapted to removably receive a lip-stick holder, the button for the slide of said holder being exposed for use in withdrawing the holder from the housing, said housing being at the 10 top of said cover and having a closed rear end and an open front end to admit and permit the withdrawal of the holder, and said button on the holder being adapted to engage the housing at its open end.
- 15 2. A combination vanity structure of the character described comprising a shallow box having a displaceable cover and affording a container for toilet articles, said cover having as a part thereof a housing extending transversely of the box adapted to removably receive a lip-stick holder, the button for the slide of said holder being exposed for use in withdrawing the holder from the housing, said housing being at the 20 top of said cover and extending transversely thereof and being less in length than the diameter of the cover, and said housing being closed at one end and open at its entering end and the metal of the cover outwardly from said open end being inclined downwardly toward said open end.
- 25 3. A combination vanity structure of the character described comprising a shallow box having a displaceable cover and affording a container for toilet articles, said cover having as a part thereof a housing extending transversely of the box adapted to removably receive a lip-stick holder, the button for the slide of said holder being exposed for use in withdrawing the holder from the housing, said housing being pressed upwardly from said cover and closed at one 30 top of said cover and extending transversely thereof and being integral with the top of said cover and having a closed rear end and an open front end to admit
- 35
- 40
- 45

and permit the withdrawal of the holder. 50

4. A combination vanity structure of the character described comprising a shallow box having a displaceable cover containing a mirror and said box being adapted to hold small toilet articles, and said cover having as a part and at the top thereof a housing extending transversely of the box adapted to removably receive a lip-stick holder, the button for the slide of said holder being exposed for use in withdrawing the holder 60 from the housing.

5. A combination vanity structure of the character described comprising a shallow box having a displaceable cover containing a mirror and said box being adapted to hold small toilet articles, and said cover having as a part and at the top thereof a housing extending transversely of the box adapted to removably receive a lip-stick holder, the button for the slide of said holder being exposed for use in withdrawing the holder from the housing, said housing being closed at one end and open at its receiving end and provision being made to protect the back of the mirror from being injured by said 75 holder.

6. A combination vanity structure of the character described comprising a shallow box having a displaceable cover containing a mirror and said box being adapted to hold small toilet articles, and said cover having as a part and at the top thereof a housing extending transversely of the box adapted to removably receive a lip-stick holder, the button for the slide of said holder being exposed for use in withdrawing the holder from the housing, said housing being pressed upwardly from said cover and closed at one end and open at the other end, and said housing at opposite sides of its end portions being pressed toward each other to form seats for said holder and support said holder upwardly from the back of said mirror. 85

In testimony whereof we have hereunto signed our names at New York city, New 90 York, this 12th day of January, 1923.

NATHAN KASDAN.
DANIEL POLLACK.
